BY ATTORNEY

UNITED STATES PATENT OFFICE.

HARRY AZZI, OF NEW YORK, N. Y.

AUTOMATICALLY-OPERATED RAILROAD GATE.

Application filed October 5, 1923. Serial No. 666,848.

To all whom it may concern:

Be it known that I, HARRY AZZI, a citizen of the United States, residing at New York, in the county of New York and State 5 of New York, have invented certain new and useful Improvements in Automatically-Operated Railroad Gates, of which the following is a specification.

This invention relates generally to automatically operated railroad gates, which are adapted for operation by passing trains, the invention having for an object the provision of an automatically operated railroad gate of simple construction.

15 For further comprehension of the invention, and of the objects and advantages thereof, reference will be had to the following description and accompanying drawing, and to the appended claims in which 20 the various novel features of the invention are more particularly set forth.

Fig. 1 of the drawings is a side elevational view showing the invention applied to a railroad track.

25 Fig. 2 is a detail sectional elevation of the operating element.

Fig. 3 is a fragmentary elevational view at right angles to Fig. 2.

30 Fig. 4 is a plan view, omitting the lower parts of the device.

Referring now to the drawing, the reference numeral 10 indicates in side view an ordinary railroad track. According to my invention I mount at a suitable point preferably between the track rails a vertical guide element 12 which is located below the level of the rails in a suitable recess in the roadbed, this guide element being open at the top, and closed at the bottom by a member 12'.

40 Freely slideable in this guide element, and projecting from the top thereof, is a plunger 14 on the upper end of which is a horizontally projecting head 15, this head extending longitudinally of the track. This head is formed with dovetail tongues 15' engaging in complementary grooves in a bar 17 which seats thereon. The head 15 may be reinforced by a strut 18 connected at opposite ends thereto and to the plunger 14, this strut passing through a vertical slot 19 in the guide element 12.

45 The bar 17 is pressed toward the rail by means of springs 17' which bear between 50 the bar and a flange 15' on the head 15.

This bar is arranged to present an inclined top surface, while the side thereof which is turned toward the rail is beveled off at one end as at 17'.

Freely slideable in the guide element 12, below the plunger 14, is a disk 20 having a diminished rod or stem 21 which extends downward through the bottom 12' of the guide element. The projecting lower end of this stem is connected, by a slot and pin 60 connection 22, with one end of a lever 24 fulcrumed between its ends as at 23 to a lug on the guide member, the opposite end of this lever having formed thereon a gear segment 25 which meshes with a gear pinion 26 to which is fixed co-axially a pulley 27. Connected at one end to this pulley is a rope 28 which leads over suitable guide pulleys to connect to a gate bar 30 fulcrumed as at 31 on a standard 32 and normally held 75 vertically by a counterweight 33.

Interposed between the top of the guide element 12 and the bar 15 on the plunger are a pair of coiled expansion springs 38 which act to move the plunger 14 upward 80 after depression by the train. Another expansion spring 39 is interposed between the plunger and the disk 20 and acts to transmit downward movement of the plunger to the disk. Movement of the disk away from 85 the plunger is limited by a rope or chain 40 connected at opposite ends respectively to the plunger and disk.

The plunger 14 is adapted to be retained in lowered position until after the train has 90 passed the crossing by means of a bolt 43 slideable in the side of the guide element 12 and adapted to engage in a notch 44 in the side of the plunger. A spring 45 urges this bolt to locking position, the movement 95 of the bolt in this direction being limited by a collar 46 on the bolt. Connected to the outer end of the bolt 43 is a rope 47 which is led, along suitable guide elements to a release device located on the opposite side of 100 the crossing. This release device comprises a plunger 50 having a beveled head 51 adapted to be engaged by the part carried by the train, this plunger being freely slideable in a casing 52 and being urged upward by an 105 expansion spring 53 in the latter. A pulley 54 is here shown as mounted on the casing and the rope 47 is led over the top of said pulley and downward to connect to a finger 55 fixed to the plunger and projecting 110

through a vertical slot in the side of the casting 52.

In order that the gate 30 may not be operated with too great violence when the 5 plunger 14 is depressed I provide a pair of dash-pots 60 which slow down the movement of the disk 20, these dash-pots being here shown as mounted on the bottom 12' of the guide element and having their plungers 61 10 connected to the disk.

When the train approaches the crossing in the direction of the arrow in Fig. 1, a suitable part thereon such as indicated at 65 in Fig. 3, and which is arranged to present a 15 laterally projected finger, engages the bar 17 and depresses the plunger, the bolt 43 snapping into the notch 44 and holding the plunger depressed. Since the dash-pots 60 prevent rapid movement of the disk 20 the 20 plunger compresses the spring 39 and the latter moves the disk at a slower rate of speed causing the gate 30 to be closed. After the train has passed the crossing the plunger 50 is depressed by the part 65 and the bolt 43 25 retracted, the springs 38 returning the plunger 14 and connected parts to normal position, the counterweight 33 causing the gate to swing open. Should a train be traveling in an opposite direction the part 65 30 will engage the beveled end 17' of the bar 17 and move the latter to one side without depressing the said bar or operating the device.

The gate 30 may be provided with a glass 35 covered casing 69 on which the word "Stop" is shown, and a lamp may be provided in said casing to be illuminated by the closing of a pair of contacts 70 and 71.

Having thus described my invention what 40 I claim as new and desire to protect by Letters Patent of the United States is as follows:

1. In a railroad gate, a gate proper, an element adapted for operation by a train, 45 a second element adapted for operation by the first, an operative connection between said second element and the gate proper, and an expansion spring bearing between said first and second elements, and a dash-pot engaged with said second element to transmit 50 movement from the first to the second element to retard the movement thereof.

2. In a railroad gate, a gate proper, a plunger adapted for operation by a train, 55 a guide element for said plunger, a member slideable in said guide element under said plunger, an operative connection between said member and the gate proper, an ex-

pansion spring interposed between said plunger and member, a flexible connecting element limiting movement of said plunger and member away from one another, and a dash-pot adapted to retard movement of said member.

3. In a railroad gate, a gate proper, a plunger adapted for operation by a train, a 65 guide element for said plunger, a member slideable in said guide element under said plunger, an operative connection between said member and the gate proper, an expansion spring interposed between said plunger and member, a flexible connecting element limiting movement of said plunger and member away from one another, and a dash-pot adapted to retard movement of said member, a spring adapted to move said plunger upward, and a bolt for holding said plunger depressed.

4. In a railroad gate, a gate proper, a plunger adapted for operation by a train, 80 a guide element for said plunger, a member slideable in said guide element under said plunger, and operative connection between said member and the gate proper, an expansion spring interposed between said plunger and member, a flexible connecting element limiting movement of said plunger and member away from one another, and a dash-pot adapted to retard movement of said member, a transversely slideable bar on 85 said plunger adapted to be engaged by the train.

5. In a railroad gate, a gate proper, a plunger adapted for operation by a train, a guide element for said plunger, a member 90 slideable in said guide element under said plunger, an operative connection between said member and the gate proper, an expansion spring interposed between said plunger and member, a flexible connecting element limiting movement of said plunger and member away from one another, a dash-pot adapted to retard movement of said member, a spring adapted to move said plunger upward, a bolt for holding said 100 plunger depressed, said bolt being adapted to automatically engage with said plunger when the latter is depressed, a second plunger adapted for operation by a train, and an operative connection between said 105 second plunger and said bolt adapted to cause release of said bolt upon depression of said second plunger.

In testimony whereof I have affixed my signature.

HARRY AZZI.
